UNITED STATES PATENT OFFICE.

OTTO BRUECK, OF JERSEY CITY HEIGHTS, NEW JERSEY.

PACKING FOR PARTITIONS FOR WASHTUBS AND THE LIKE.

No. 836,628.

Specification of Letters Patent.

Patented Nov. 20, 1906.

Application filed June 12, 1905. Serial No. 264,841.

To all whom it may concern:

Be it known that I, OTTO BRUECK, a citizen of the United States, residing at Jersey City Heights, in the county of Hudson and State of New Jersey, have invented new and useful Improvements in Packing for Partitions for Washtubs and the Like, of which the following is a specification.

Washtubs have been made with movable partitions, which enable the tub to be used for various other purposes than washing—such, for example, as bathing.

This invention relates to improvements in devices such as shown in United States Patent No. 523,621, dated July 24, 1894, for washtub.

In the drawings accompanying this application is shown the packing embodying this invention and adapted to be applied to a washtub-partition.

In the drawings, Figure 1 is a plan view of a washtub with this invention applied. Fig. 2 is a section along x x , Fig. 1. Fig. 3 is a perspective view of a packing.

When the rubber packing 11 in this patent structure becomes worn, it leaks and must be thrown away. By making the packing with a slit 11', as shown above, an expander, such as a piece of rope or the like, can be crowded into this slit and the packing made to fit tight or spread to make perfect closure.

The washtub can have the movable partition formed as usual, and the packing 11 made to project from the partition. The projecting part of the packing being slotted, as stated, becomes expansible and allows a spreader to be inserted or seated in the packing. In this improved structure a metallic plate is secured to the bottom and to the front and rear walls of the tub and provided with a seat to receive the packing-strip of the

movable partition, the slotted edge of the packing with the expander therein being inserted in the said seat. This metallic plate with the seat is clearly disclosed in my Letters Patent before mentioned, and by the addition of the slit 11' and the expander in the packing material advantages result in the operation and effectiveness of the partition.

A metallic plate E extends across the bottom of the tub and up on the front and rear walls of the latter and is provided with two openings 12 and 13 and an overflow-channel 14. The openings 12 and 13 communicate with the waste-pipe 15 through the overflow-channel 14.

What I claim as my invention, and desire to secure by Letters Patent, is—

The combination with a tub, of a metallic plate secured to the tub-bottom and to the front and rear walls of the tub and having a socket formed in the inner edge thereof and waste-openings extending throughout the length of the plate on opposite sides of the socket, outlet means communicating with the lower portion of the tub and the waste-openings, and a movable partition having a packing-strip secured in the outer edge thereof and fitted in the said socket of the plate and having a slit opening through the edge engaging the socket, and an expanding material crowded into the slit to cause the packing-strip to tightly fit in the socket and form a water-tight joint.

In testimony whereof I have hereunto set my hand in the presence of two subscribing witnesses.

OTTO BRUECK.
